Primary Examiner — T Chase Nelson(74) *Attorney, Agent, or Firm* — CASIMIR JONES, S.C.;
Thomas J. Lyneis(57) **CLAIM**

The ornamental design for a contact lens package, as shown and described.

DESCRIPTION

FIG. 1 is a perspective view of a contact lens package showing our new design.

FIG. 2 is a top plan view thereof.

FIG. 3 is a right side elevational view thereof.

FIG. 4 is a bottom plan view thereof.

FIG. 5 is a left side elevational view thereof.

FIG. 6 is a rear elevational view thereof; and,

FIG. 7 is a front elevational view thereof.

The broken lines in the drawings show portions of the contact lens package that form no part of the claimed design.

1 Claim, 4 Drawing Sheets# US D1,062,223 S
